UNITED STATES PATENT OFFICE.

SAM H. LIBBY, OF EAST ORANGE, NEW JERSEY, ASSIGNOR TO SPRAGUE ELECTRIC COMPANY,
A CORPORATION OF NEW JERSEY.

AUTOMATIC CARRIER SYSTEM.

No. 904,789.

Specification of Letters Patent. Patented Nov. 24, 1908.

Application filed March 12, 1906. Serial No. 305,440.

To all whom it may concern:

Be it known that I, SAM H. LIBBY, a citizen of the United States, residing at East Orange, county of Essex, State of New Jersey, have invented certain new and useful Improvements in Automatic Carrier Systems, of which the following is a specification.

The present invention relates to systems wherein a carrier is adapted to be set in operation at one point and thereafter travel to another point where it is automatically reversed and returned to the starting point, and has for its object to provide a simple construction and arrangement of parts whereby the carrier may be made to operate smoothly and with certainty, with the least wear upon the system and without requiring careful attention on the part of the operator.

To the above end the present invention consists in the construction and arrangement of parts to be hereinafter described and particularly pointed out in the claims.

The present invention will be more fully understood and its objects and advantages will more clearly appear from the following description taken in connection with the accompanying drawings wherein:

Figure 1 illustrates diagrammatically the motor and control mechanism of the carrier, together with a plurality of stations and the system of current distribution between the stations arranged in accordance with a preferred embodiment of the present invention; and Fig. 2 shows a modification of the system of current distribution between two stations.

Reference being had to Fig. 1, A indicates a motor for moving a carrier along its track.

B is a hoisting motor mounted upon the carrier.

C is a reversing switch associated with the motor A.

D is a controller for the hoisting motor.

E is a limit switch of the usual type adapted to open the circuit of the hoisting motor and operate the reversing switch of the traverse motor in order to stop the hoisting motor after the load has been raised and to set the traverse motor in operation to move the carrier toward the dumping station.

L and L' indicate a source of current supply from which current is taken to operate the motors.

The carrier is provided with a current col-

lector F which is adapted to engage with a supply conductor l connected to line L'. Two other current collectors F¹ and F² are provided, these collectors engaging with a supply conductor l but being separated from each other for a considerable distance for a purpose to be hereinafter described.

The supply conductor l is made continuous throughout the entire distance over which the carrier is adapted to travel, while the supply conductor l is made in sections, the main sections 1 and 2 being arranged between the loading station and the first unloading station and between two unloading stations, respectively. At the loading station the conductor l is provided with a dead section 3, while at the dumping or unloading stations dead sections 4 and 5 are provided. Additional sections 7, 8 and 9, normally isolated from each other and from the main sections, are arranged near the loading station. Sections 1 and 2 are connected directly to line L, while sections 4 and 5 may be connected to the same line through switches 10 and 11, respectively. The sections 7, 8 and 9 are likewise connected to line L: the connection between section 7 and the line including resistance sections R, R¹ and R²; the connection between section 8 and the line including resistance sections R¹ and R²; and the connection between the section 9 and the line including only resistance section R². Section 9^a may be connected to line L through resistance R³ by the switch 12. Similarly, sections 8^a and 7^a may be connected to line L through resistances R⁴ and R⁵ and through resistances R, R¹ and R², respectively, by means of switches 13 and 14. The sections 7^a, 8^a and 9^a may also be connected together and to the main section 1 by moving the switches 12, 13 and 14 into the positions shown. Similarly, sections 9^b, 8^b and 7^b may be connected to line L or to each other and to the main section 2 by moving switches 15, 16 and 17 to one position or the other. In the drawing, one group of auxiliary sections is shown disconnected from line L and connected to the section 1, while the other group is disconnected from the section 2 and connected to line L. This arrangement may of course be extended to include any number of unloading stations.

Assuming that the parts are in the positions illustrated, current will flow from line L', supply conductor l, current collector F,

field coil a of the traverse motor, through contacts c , c^1 and c^2 of the reversing switch, through the armature a^1 of the traverse motor and then through contacts c^3 , c^4 and c^6 5 of the reversing switch to current collector F^1 , sections 7 of the other supply conductor, resistances R , R^1 and R^2 to line L . Thus the motor is being supplied with a low current and the carrier is started toward the un- 10 loading stations at a slow speed. As soon as the current collector F^1 enters upon section 8, the resistance R is eliminated and only resistances R^1 and R^2 remain in circuit between the source of supply and the carrier: 15 consequently the speed of the carrier is accelerated. When section 9 is reached a further resistance section, R^1 , is eliminated and a still higher speed is reached. Finally, the carriage enters upon the main section 1 and 20 all the resistance is eliminated, permitting the carrier to proceed at its maximum speed toward the dumping station.

If it is not desired to stop at the first unloading station, the switches 10, 12, 13 and 25 14 are moved into the positions shown, causing the sections 7^a, 8^a and 9^a to be in electrical connection with section 1, and the normally dead section 4 to be supplied with current directly from line L . The carrier therefore travels past the first unloading station and, if it is desired to stop at the next unloading station, the switches 11, 15, 16 and 30 17, are moved to the positions indicated. Thus when section 9^b is reached, the only 35 path through which current may flow after leaving collector F^1 is through switch 15, resistance section R^2 , and thence to line L . This insertion of resistance in the circuit of the motor cuts down its speed and consequently causes the speed of the carrier itself to diminish. In like manner, as sections 8^b and 7^b are reached, additional resistance sections R^1 and R are cut in, so that when the carrier enters upon dead section 5 its speed 40 has been materially reduced. It will be seen that as soon as the dead section is reached the motor circuit is interrupted and the carrier is brought to a stop through the action of the solenoid brake A^1 . Before the carrier 45 comes to rest, however, a projection G^1 at the unloading station is struck by an arm 18 on the carrier. This arm normally, it will be seen, engages with a cam 19 upon the reversing switch and holds the reversing 50 switch in the position shown, against the tension of a spring 20. When, therefore, the arm 18 strikes against the projection G , the cam 19 is released and the reversing switch is thrown to its opposite running position by means of the spring 20. Current 55 is now supplied to the traverse motor through current collector F^2 which is in engagement with section 7^b, and a circuit may be traced from supply conductor l^1 through 60 the field coil of the traverse motor, through

contacts c^1 , c^8 , c^7 and c^8 of the reversing switch, through the armature of the traverse motor, through reverser contacts c^2 , c^8 , c^8 and c^{10} , to collector F^2 , through switch 17 and resistances R , R^1 and R^2 to line L . The 70 carrier therefore starts slowly on its return trip and, as sections 8^b and 9^b are reached, resistance sections R and R^1 are cut out, and finally, when the carrier enters upon section 2, resistance section R^2 is also cut out, so that 75 the carrier travels towards the loading station at full speed. When section 9 is reached, resistance R^2 is cut in and resistances R^1 and R are also introduced in the order named, as sections 8 and 7 are reached. 80 Therefore the carrier, when it arrives at the loading station, is traveling at a low rate of speed, so that when the circuit is interrupted at section 3 the carrier may be readily brought to a stop. If it had been desired to 85 unload at the first unloading station, the switches 10, 12, 13 and 14 would have been moved into the opposite positions from those shown and the carrier would have been slowed down, stopped and reversed at the 90 first station, the reversing switch being tripped by means of the projection G which was previously adjusted out of the path of movement of the arm 18.

It is of course understood that the load 95 may be dumped in any suitable way at the desired station, this portion of the apparatus being omitted since it forms no part of the present invention.

It will now be seen that a very effective 100 system of control for the carrier is provided, whereby it is possible to set the carrier in operation while bearing a heavy load without danger of injury to the motor, to thereafter permit the carrier to travel at its maximum speed and then to slow down the carrier in order that the reversal may take place without unduly straining the apparatus. Similarly, the return of the carrier to the starting point is effected in the same 105 smooth and efficient manner. By placing the resistance in the distributing circuit instead of in the circuit upon the carrier, the use of all speed controlling apparatus on the carrier is avoided and the dead weight 110 upon the carrier due to this apparatus and the heavy resistances is materially reduced, while at the same time, by reason of the avoidance of movable controller parts, a system results which may be subjected to much 115 rough usage without in any way affecting the certainty and efficiency of its operation.

The switches for controlling the auxiliary sections at the dumping stations may be controlled in any suitable manner, as may also the tripping devices G and G^1 . No means for operating these devices has been illustrated since means for accomplishing this purpose, either in the way of distant control or local control, is well known. 120 125 130

- In Fig. 2 I have indicated a similar system wherein but one resistance section is employed and in which there is but one unloading station. Thus the elements L, L¹, l, l¹, 5 F, F¹, F², R and G correspond in every respect to the elements bearing similar reference characters in Fig. 1. The supply conductor l instead of having three auxiliary resistance governing sections at each station 10 is provided with only one such section, namely, a section 21 at the loading station and a section 21^a at the dumping station.

What I claim as new and desire to secure by Letters Patent of the United States, is,—

1. In a traveling carrier system, a loading station and an unloading station, a supply conductor connecting said stations and having a dead section at the unloading station, a carrier having a pair of separated current 15 collectors engaging said conductor, a driving motor on said carrier, a reversing switch arranged to connect said motor to one of said current-collectors for movement in one direction and to the other current-collector 20 for movement in the opposite direction, and means for automatically operating said reversing switch at the unloading station.

2. In a traveling carrier system, a loading station and an unloading station, a supply conductor connecting the stations and having dead sections at the stations, a carrier having a pair of separated current-collectors engaging said conductor, a driving motor on said carrier, a reversing switch arranged 25 to connect said motor to one current-collector for one direction of movement and to the other current-collector for movement in the opposite direction, and means for stopping said carrier when the current-collector 30 which is supplying current to the motor runs upon one of said dead sections.

3. In a traveling carrier system, a loading station and an unloading station, a supply conductor connecting said stations and having a dead section at the unloading station, a carrier having a pair of separated current collectors engaging said conductor, a driving motor on said carrier, a reversing switch arranged 35 to connect said motor to one of said current-collectors for movement in one direction and to the other current-collector for movement in the opposite direction, and means for automatically operating said reversing switch at the unloading station.

4. In a traveling carrier system, a loading station and a plurality of unloading stations, a supply conductor connecting said stations and having isolated sections adjacent said unloading stations, means for energizing or deenergizing said isolated sections, a carrier having a pair of separated current-collectors engaging said conductor, a driving motor on said carrier, a reversing switch arranged 40 to connect said motor to one of said current-collectors for movement in one direction and to the other current-collector for movement in the opposite direction, and means for automatically operating said reversing switch at the unloading station.

5. In a traveling carrier system, a loading station and to the other current-collector for movement in the opposite direction, and means for automatically operating said reversing switch at the unloading station.

6. In a traveling carrier system, a loading station and an unloading station, a supply conductor connecting said stations and having dead sections adjacent said stations, a carrier having a pair of separated current-collectors engaging said conductor, a driving motor on said carrier, a reversing switch arranged to connect said motor to one current-collector for movement in one direction and to the other current-collector for movement in the opposite direction, an electromagnetically-controlled brake adapted to stop said carrier when the current-collector which is supplying current to the motors enters upon a dead section, and a projection at the unloading station arranged to cause the operation of the reversing switch.

7. In a traveling carrier system, a loading station and a plurality of unloading stations, a source of current supply, a conductor connected to said source of supply and extending between said stations, isolated sections in said conductor adjacent said unloading stations, switches for connecting said isolated sections to the source of current supply, a carrier having a pair of separated current-collectors engaging said conductor, a motor for driving said carrier, a reversing switch arranged to connect said motor to one of said current-collectors for movement in one direction and to the other current-collector for movement in the opposite direction, and a device adjacent each unloading station adapted to be set to cause the operation of the reversing switch before the idle current-collector enters upon the corresponding isolated section in passing from the loading station to the unloading station.

8. In a traveling carrier system, a loading station and a plurality of unloading stations, a source of current supply, a conductor extending between said stations, said conductor comprising dead sections at each station and main sections between stations connected to said source of supply together with isolated sections near each station connected to said source of supply through a resistance or resistances, switches for connecting said dead sections to the source of current supply, switches for connecting said isolated sections directly to the source of supply, and a current-collector engaging said conductor.

9. In a traveling carrier system, a loading station and a plurality of unloading stations, a source of current supply, an electrically-operated carrier adapted to travel between said stations, a resistance located at a fixed point and means for connecting said carrier to the source of current supply through said resistance at the loading station, for cutting

out said resistance as the carrier leaves the loading station and cutting the resistance in again as the carrier approaches any predetermined unloading station, together with means for stopping said carrier at said latter station and connecting it to the source of current supply for movement toward the loading station.

9. In a traveling carrier system, a loading station and a plurality of unloading stations, a source of current supply, an electrically-operated carrier adapted to travel between said stations, a resistance located at a fixed point and means for connecting said carrier to said source of current supply through said resistance in starting the carrier from any station and when the carrier approaches any predetermined station and for eliminating said resistance while the carrier is between stations, together with means for reversing said carrier at any predetermined unloading station, and means for stopping the carrier at the loading station.

10. In a traveling carrier system, a loading station and an unloading station, a source of

current supply, a resistance, a motor-driven carrier adapted to travel between said stations, a conductor for supplying current to said carrier, said conductor comprising a main section extending between said stations and connected to said source of current supply together with auxiliary sections at the ends of the main sections and dead sections at the stations, means for connecting said auxiliary sections to the source of supply through said resistance, a pair of separated current collectors on said carrier arranged to be alternately connected to the carrier-motor for opposite directions of movement of the carrier, and means for stopping the carrier when the active current collector enters upon a dead section, the arrangement being such that the carrier is stopped before both collectors enter upon the dead section.

In witness whereof, I have hereunto set my hand this eighth day of March, 1906.

SAM H. LIBBY.
